UNITED STATES PATENT OFFICE.

THOMAS S. CATLIN, OF WAVELAND, INDIANA.

DESIGN FOR A SIGNAL-LAMP CASING.

Application filed September 29, 1925. Serial No. 14,938. Term of patent 14 years.

To all whom it may concern:

Be it known that I, THOMAS S. CATLIN, a citizen of the United States, residing at Waveland, in the county of Montgomery and State of Indiana, have invented a new, original, and ornamental Design for Signal-Lamp Casing, of which the following is a specification, reference being had to the accompanying drawing, forming part thereof.

In the drawing:

Figure 1 is a front elevation of the signal lamp casing, and,

Figure 2 is a section thereof, showing my new design.

What I claim is:

The ornamental design for a signal lamp casing, as shown.

THOMAS S. CATLIN.
